LEVELING CONTROL SYSTEM FOR ROAD
BUILDING MACHINES

Raymond A. Gurries, San Jose, and John Curlett, Los Gatos, Calif., assignors to Gurries Manufacturing Co., San Jose, Calif., a corporation of California
Filed May 9, 1961, Ser. No. 108,902
15 Claims. (Cl. 94—39)

This invention relates to road building machines and more particularly to a grade-wire hanger and a wire fork centering support used in connection with leveling control systems for road building machines.

Practically all road building machines comprise: A plurality of traction units engaging the ground for supporting and moving the road building machine; one or more road building tools such as striker blades, scrapers, conveyor screws, hoppers; and support means connecting the road building tools to the traction units. Since the traction units are in direct contact with the ground where grade, cross grade and general surface conditions are usually different from the road surface level to be constructed, it is essential that the support means provide for vertical adjustment between the road building tools and the traction units to permit the maintaining of the position of the road building tool at an accurate and predetermined level reflecting a desired grade and cross grade irrespective of the grade, cross grade and irregularities of the ground engaged by the traction unit.

Supports, which provide for vertical adjustment of the road building tool, conventionally may include, for example, valve operated hydraulic rams, solenoid actuated motorized worm and pinion or cam and cam follower combinations as well known to those skilled in the art. The valves or solenoids or other control means are actuated whenever the road building tool deviates from the desired height, grade and cross grade. Conventionally, the control means for actuating the individual supports include horizontally disposed wire forks mounted to the road building tool or the frame carrying the tool and which engages, in straddle fashion, a tautly strung grade-wire supported at the desired grade along the side of the road in wire hangers mounted upon stakes anchored into the ground. The wire fork traces the wire and any deviation of the angular position of the fork from a predetermined angular position (usually horizontal) constitutes an error signal which is utilized to actuate the supports and thereby the vertical height of the tool to bring the wire fork back to its predetermined angular position. The wire fork may be connected to a shaft which either directly or through a suitable mechanical linkage actuates the hydraulic valves or solenoids or may be pivotally mounted to close and open micro switches which operate the hydraulic valves or solenoids as is well known.

The wire hangers of the prior art devices presented a blocking obstacle to the smooth flow of the wire tracing wire fork requiring the wire fork to swivel out of the path of the wire hanger to clear it. For this reason the wire fork was swivelly mounted upon a vertical axis and included a spring centering means to restore the wire fork to its control position after the obstacle had been cleared. During the instance of time when the wire fork was swiveled back, the leveling control was temporarily interrupted, at least to a certain degree. Positive control was restored when the wire hanger was cleared and the wire fork jumped back to its central position. In case of great road irregularity, the wire fork often completely disengages itself from the grade wire in its swiveled back position requiring stoppage of the road building machine until the fork was once more engaging the grade-wire.

2

Also the constant swiveling action puts severe stress upon the spring centering means necessitating its frequent replacement.

It is therefore an object of this invention to provide a wire fork and wire hanger combination in which the wire fork can smoothly pass over the wire hanger remaining at all times centered on the grade-wire in its transversely extended position.

It is a further object of this invention to provide an improved wire fork centering means which is more rugged, reliable and economical than those used heretofore.

It is still another object of this invention to provide a wire hanger of a novel configuration which permits the wire fork to gradually spread its prongs upon encountering the hanger to clear it and which supports the grade-wire so that the spreading wire fork is always centered on the grade-wire.

It is still a further object of this invention to provide a wire hanger of novel configuration and a wire fork centering means to keep the wire fork in engagement with the grade-wire to thereby insure smooth operation and constant control of the leveling system.

In accordance with a preferred embodiment of this invention, the wire hanger includes a fork spreading plate mounted at right angles to the wire carrying end of the wire hanger. The vertical dimension of the fork spreading plate decreases from its mid-portion in both directions thereby following the shape of an oval. The plate also has narrow end portions to permit the prongs of the wire fork to engage opposite surfaces of the plate and to spread slowly over both sides thereof, and after passing to return to their normal contracted position. The wire runs behind the plate and centrally with respect thereto so that the wire fork is always centered on the grade-wire. In order to permit the wire fork to spread around the wire hanger rather than to pivot away from it, a firm flexible support is provided which keeps the feeler fork in its outwardly extended position unless the obstacle encountered by the far end of the wire fork is greater than the spreading action necessary to negotiate the plate.

Other objects and a better understanding of this invention may be had by reference to the following specifications and appended claims and the drawings in which:

FIGURE 1 shows a side view of the wire hanger and the wire fork of this invention in which the wire fork is pivotally supported by the road building machine and actuates the supports by translational motion;

FIGURE 2 shows an enlarged top view of the wire fork of this invention in which the wire fork is connected to a shaft and actuates the supports through rotation of that support shaft;

FIGURE 3 shows an enlarged front view of the fork shield of the wire hanger;

FIGURE 4 shows a side view of the fork shield of FIGURE 3, together with the engaging prong portions of the wire fork; and

FIGURE 5 shows, in perspective view, the wire hanger mounted upon a ground stake and several progressive stages of prong engagement and prong spreading of the wire fork upon straddling the fork shield.

Referring now to the drawings, in which like reference characters designate like parts, there is shown in FIGURE 1 a stake 10 which may be made of steel having a circular cross section and which supports a wire hanger 12 having a boss 14 with an opening dimensioned for sliding engagement with stake 10. Boss 14 is provided with an end boss 16 having a threaded hole to accommodate set screw 18. Set screw 18 is tightened against stake 10 to secure wire hanger 12 thereto. Wire hanger 12 includes a short slot 20 (FIGURE 4) for accommodating grade

wire 21 and a fork spreading plate 22, an enlarged view of which is shown in FIGURE 3. A wire fork 24 shown in engagement with the wire 21 has its inner closed end supportably inserted into a swivelable sleeve 26 and is fastened thereto by a retainer key 28 held in place by a set screw 30 so that its prongs 95 and 96 lie in a vertical plane. Spacer pin 32 abuts the closed end of wire fork 24 and prevents it from sliding inwards into sleeve 26.

One end of sleeve 26 is provided with a cylindrical boss 34 which is rotatably supported about a pin 36 in a forked bracket 38 permitting sleeve 26 to pivot in a horizontal plane. Clamped to one prong of forked bracket 38 is a forked support 40 which has welded or otherwise firmly attached thereto one end of a closely wound extension spring 42 for centering sleeve 26. The other end of extension spring 42 is rigidly connected to a centering shaft 44 which rides in a hole 48 contained in a centering brace 46 welded to or otherwise affixed to sleeve 26. To facilitate the insertion of centering shaft 44 into hole 48, forked support 40 is held in place by a screw 41 which permits its removal from bracket 38.

Forked bracket 38 is suitably fastened to a cylindrical hub 80 which is pivotably mounted upon a pivot shaft 82. Pivot shaft 82 is connected to the tool or tool carrying portion of the road building machine (not shown) in such a way that its axis is parallel to the normal direction of motion of the road building machine. An arm 84 is affixed to hub 80, preferably but not necessarily axially with and diametrically opposed to sleeve 26, to which some means, illustrated schematically as a lever 85, is attached which communicates with a support actuating mechanism 86. Support actuating mechanism forms no part of this invention and may comprise, as already stated, mechanical or electrical actuating members connected, either directly or indirectly, to hydraulic valves or electrical solenoids or switches which actuate the supports. A counterweight 73 may be slidably supported by arm 84 to provide balance about pin 82.

Referring now to FIGURE 2, there is shown the same wire fork as in FIGURE 1 supported by forked bracket 38 but instead of connecting bracket 38 to a pivotable hub and operating the actuating mechanism by lever 85 connected to arm 84, bracket 38 is connected to a hub 50 which is either directly or indirectly (as illustrated) mounted upon a rotatable shaft 66 which operates a support actuating mechanism 56. Support actuating mechanism 56 just as mechanism 86 forms no part of this invention and may comprise, as previously stated, mechanical or electrical actuating members connected either directly or indirectly to the means in the supports which provide the vertical adjustment.

Hub 50, as stated, may be directly connected to shaft 66 which just like pivot shaft 82 is connected to the tool or tool carrying frame of the road building machine and which has its axis parallel to the side of the road building machine. If directly connected to shaft 66, hub 50 comprises a cylindrical sleeve having an inner bore dimensioned for engagement with shaft 66 and including some means for firmly fastening it to shaft 66. Such means may comprise a set screw through one side of hub 50, a key accommodated in a key way or other suitable means.

In some applications, where the angular deviation of shaft 66 is to be limited to a maximum value, hub 50 may be provided with an angular overload assembly generally designated by reference character 54. Angular overload assembly 54 is fully described in a copending application, Serial No. 862,276, filed December 28, 1959. Briefly, assembly 54 comprises hub 50 rotatably mounted about a spindle 60 having a flange 62 and a cylindrical bore 64 dimensioned for engagement with shaft 66. Another flange 63 of substantially the same configuration as flange 62 is mounted upon the lower end of spindle 60. Shaft 66 passes through cylindrical bore 64 and is conventionally secured to spindle 60. Between hub 50 and flanges 62 and 63, respectively, two axially spaced circular

chambers 67 and 69 are formed for accommodating a pair of torsion springs 70 and 71. Torsion springs 70 and 71 have their respective ends tied to hub 50 and flanges 62, 63. As long as the change in angular position of sleeve 26 about shaft 66 is smaller than maximum amount, angular overload assembly 54 through torsion springs 70 and 71 make spindle 60 follow hub 50. If the change in angular position is greater than the maximum displacement permitted shaft 66, hub 50 puts torsion springs 70 and 71 under torsion and spindle 60 is not forced past the maximum allowable angular displacement of shaft 66.

Hub 50 may be provided with a counterweight 73 adjustably mounted on an arm 72 to counteract the torque on hub 50 due to the weight of sleeve 26, wire fork 24 and spring 42.

Referring now to FIGURE 3, fork spreading plate 22 is provided with a diagonally extending slot 90 which either communicates directly with short slot 20 holding grade wire 21 in its horizontal position or which extends past plate 22 and actually forms short slot 20. The angle formed between slot 90 and wire 21 is illustrated as being about 30 degrees so that grade-wire 21 need not be unnecessarily stretched when inserted and once inserted will be secure in slot 20 against inadvertent dislodgement. The width of the slot is preferably considerably wider than the grade-wire so that if slot 20 is formed by extending slot 90 past plate 22, grade-wire 21 may lie horizontally despite the diagonal inclination of the slot. The contour of fork spreading plate 22 comprises two substantially identical arcuate surfaces 92 and 94 intersecting in two places to form edges 97 and 98. The particular curvature of arcuate surfaces 92 and 94 is not very important—they may be circular, parabolic, oval or elliptical. What is important is that the vertical distance between surfaces 92 and 94 increases gradually from edge 97 to a maximum and then decreases gradually towards edge 98. Additionally, surfaces 92 and 94 are symmetric about grade wire 21 so that the vertical distances from either surface to wire 21 is the same. Fork spreading plate 22 may be cast as an integral part of wire hanger 12, or may be a separately manufactured plate bolted thereto.

FIGURE 3 also shows three progressive positions assumed by prongs 95 and 96 of wire fork 24 passing over fork spreading plate 22. Prior to engagement with fork spreading plate 22, prongs 95a and 96a straddle wire 21 moving from right to left towards edge 96. Thereafter prongs 95 and 96 start sliding over surfaces 92 and 94 until spread apart a maximum amount indicated by positions 95b and 96b. From that position onward, the spreading again decreases and near edge 98 the prongs are again in contact with grade-wire 21 as shown by prong positions 95c and 96c.

FIGURE 4 shows fork spreading plate 22 and wire hanger 12 as one cast piece in which short slot 20 which may be the extension of diagonal slot 90 as previously stated, holds grade-wire 21. The depth of short slot 20 need only be such that grade-wire 21 may assume its horizontal position that it may clear fork spreading plate 20. Further, prongs 95 and 96 have their ends bent away from one another to form a V portion which facilitates engaging wire fork 24 with grade-wire 21.

In operation, the end of wire fork 24 traces grade-wire 21 and since fork 24 is angularly supported either about pivot shaft 82 or about connecting shaft 66 the angular position of fork 24 will change whenever the tool or tool carrying frame height differs from the desired height as set by the grade-wire. In case of the pivot mounting illustrated in FIGURE 1, lever 85 fastened to arm 84 will initiate corrective action to restore the tool height to its proper height. In case of the shaft connected mounting illustrated in FIGURE 2, rotation of shaft 66 will actuate mechanism 56 to restore the tool to its proper height.

As the road building machine moves along grade-wire 21, wire fork 24 remains in engagement with grade-wire 21 and upon encountering wire hanger 12, its prongs 75

and 96 are spread apart to move smoothly over surfaces 92 and 94 of fork spreading plate 22 as shown in FIGURE 5. Since, as has been previously stated, surfaces 92 and 94 are equidistant from grade-wire 21, wire fork remains centered on and continues to trace grade-wire 21 during its contact with spreading plate 22 assuring constant leveling control at all times.

There may be instances when the road building machine moves closer to stake 10 than is shown in FIGURE 1 so that wire fork 24 hits stake 10. In order to avoid bending of prongs 95 and 96 and undue strain on the boom, sleeve 26 is mounted so it can pivot about a vertical axis through pin 36 and thereby yield to an insurmountable obstacle. Spring 42 keeps sleeve 26 yieldably centered permitting pivoting when fork 24 encounters a large obstacle and restore sleeve 26 to its central position immediately upon passing the obstacle.

FIGURE 2 shows sleeve 26 deflected about the center line of pin 36 and the bending of centering spring 42, which provides the restoring torque to bring it back to its normal position.

Spring 42 provides sufficient centering force to sleeve 26 so that wire fork 24 upon encountering an obstacle such as thickening plate 22, sleeve 26 remains centered allowing fork 24 to spread its prongs over plate 22. On the other hand, spring 42 does not provide sufficient centering force to permit the bending of fork 24. Furthermore, spring 42 is closely wound to provide some damping about the center position of sleeve 26 so that after being released from its pivoted position is will not oscillate to any appreciable degree. This damping is an inherent property of closely wound spring and is due to the fact that the coils on the side of greatest curvature are closely adjacent while spring action is provided by the coil separation on the side of smallest curvature. As one end of the closely wound coil is moved back and forth from normal position, a restoring force is provided by the side of the spring on which the coils separate due to spring deformation. The other side of the coil does not contribute a restoring force since there is no change, such as contraction or separation, in the individual coils. As the coil passes through its normal position, the action of the coil sides are exchanged. As a consequence of such an exchange of sides providing the restoring force, such a spring includes damping and does not cause the horizontal boom to oscillate.

Counterweight 73 is adjusted so that when fork 24 is not engaging wire 21, sleeve 26 remains horizontal. The reason for balancing arm 26 is to avoid putting a too-heavy weight on the grade-wire 21, necessitating close spaced support to prevent it from sagging. The more evenly arm 26 is balanced, the greater may be the separation between adjacent stakes since the grade wire need not support arm 26.

There has been described a wire fork centering means and a wire hanger which permits the wire fork to spread over the wire hanger and remain centered on the grade-wire when passing a wire hanger. Under ordinary operating conditions, the boom may remain horizontally extended when passing the wire hangers providing continuous tracing and thereby positive leveling control and is not subjected to the punishment of being constantly forced to yield.

What is claimed is:

1. In a road building machine in which the height of the road building tool is maintained in relation to the height of a ground supported grade-wire extending along the path of movement of said road building machine, and in which road building tool actuating mechanisms are provided for raising and lowering said tool, a height control system comprising: a fork assembly support pivotably mounted to said road building machine for movement in a plane perpendicular to the machine path of movement, a horizontally extending fork assembly horizontally pivotably connected to said support, a closely wound extension coil spring connected between 70

said support and said fork assembly, a pair of spreadable prongs extending from said fork assembly; a plurality of stakes; a wire hanger connected to each stake, said wire hanger including a short slot for supporting 5 said grade-wire and a fork spreading plate at the open end of said short slot, said fork spreading plate having a diagonally extending slot communicating with said short slot and having a vertical dimension centered about said short slot which gradually diminishes along a horizontal direction away from both sides of said short slot, said wire fork being adapted to embrace and slide along said grade wire and said coil spring providing a sufficiently stiff centering support to resist horizontal movement of said fork assembly upon engagement with a 10 fork spreading plate to cause said prongs to spread over said fork spreading plate, and means responsive to the pivotal motion of said support in said perpendicular plane and operative to actuate said tool actuating mechanism.

2. In a road building machine in which the height of the road building tool is maintained in relation to the height of a ground supported grade-wire extending along the path of movement of said road building machine by a control actuating assembly, said assembly comprising: 15 height means for changing the vertical height of said road building tool; a fork assembly support; means for pivotably supporting said fork assembly support for movement in a plane perpendicular to machine path of movement; a fork assembly swivelably connected to said support for swiveling in a horizontal plane a closely wound extension coil spring connected between said fork assembly support and said fork assembly to keep said fork assembly normally in a predetermined angular disposition in a plane parallel to machine path of movement, a pair of spreadable prongs extending from said fork assembly operative to engage said grade-wire; a plurality of stakes; and a wire hanger connected to each stake, said wire hanger including a short slot for supporting 20 said grade-wire; a fork spreading plate at the open end of said short slot, said fork spreading plate having a diagonally extending slot communicating with said short slot, the vertical dimension of said fork spreading plate being defined by concavely opposed and intersecting surfaces decreasing in separation toward the point of intersection, said coil spring providing a sufficiently 25 stiff centering support for said fork assembly to resist movement of the latter from said predetermined disposition so that engagement of said fork with said fork spreading plate causes said prongs to slide over said concavely opposed surfaces and spread, and means responsive to the angular position of said support in said perpendicular plane for actuating said height means.

3. A level control assembly for road building machines in which the height of the road building tool is maintained by a tool height control means in relation to the 30 height of a ground supported grade-wire extending along the path of movement of said road building machine comprising: a control member mounted to said road building machine for limited angular displacement about a horizontal axis, said control member being operative 35 to actuate said tool height control means in response to its angular position in a plane perpendicular to machine path of movement; a fork assembly support mounted to said control member; a fork assembly pivotably connected to said support; a closely wound extension coil spring connected between said support and said fork assembly; a pair of spreadable prongs extending from said fork assembly; a plurality of stakes; and a wire hanger connected to each stake, said wire hanger including a short slot for supporting 40 said grade-wire and a fork spreading plate at the open end of said short slot, said fork spreading plate having a diagonally extending slot communicating with said short slot and having a vertical dimension centered about said short slot which gradually decreases with increased horizontal 45 distance from said short slot, said wire fork being in 50

engagement with said grade wire and said coil spring centering said fork assembly with respect to said control shaft and providing sufficient centering force to hold said fork against horizontal displacement and cause said prongs to spread over said fork spreading plate when moved into engagement therewith.

4. A wire fork assembly for controlling the vertical tool height of a road building machine in accordance with a ground supported grade-wire extending along the path of movement of said road building machine, said wire fork assembly comprising: a control member rotatably mounted to said road building machine for limited angular displacement about an axis parallel to said grade wire, said control member being operative to actuate control means for selectively raising and lowering said vertical tool height in response to an angular position about said axis; a sleeve support mounted to said control shaft, a horizontally extending sleeve swivelly connected to said sleeve support for swiveling about a vertical axis; a closely wound extension coil spring connected between said sleeve support and said sleeve for normally centering said sleeve about an axis perpendicular to said control member; and a wire fork supported by said sleeve and operative to engage said grade wire.

5. A wire fork assembly and leveling means for maintaining the vertical tool height of a road building machine in relation to a ground supported grade-wire extending along the path of movement of said road building machine, said wire fork assembly comprising: a control shaft rotatably mounted to said road building machine for angular displacement about an horizontal axis, said control shaft being operative to actuate a control means for selective raising and lowering said road building machine in response to an angular position in a vertical plane; a sleeve support mounted to said control shaft; a horizontally extending sleeve swivelly connected to said sleeve support for swiveling about a vertical axis; a closely wound extension coil spring having an axis normally extending perpendicularly to said control shaft and intersecting said vertical axis, opposite ends of said spring being respectively connected to said sleeve support and said sleeve to resiliently support said sleeve in a central position; and a wire fork held by said sleeve and engaging said grade-wire.

6. A wire fork assembly operative to actuating a level control means for maintaining the vertical tool height of a road building machine in relation to a ground supported grade-wire extending along the path of movement of said road building machine, said wire fork assembly comprising: a support pivotably mounted to said road building machine; a horizontally extending sleeve swivelly connected to said support for swiveling about a vertical axis; a retaining plate connected to said sleeve; a closely wound extension coil spring normally extending perpendicularly to said control shaft and whose axis intersects said vertical axis, one end of said spring being fixed to said sleeve support and the other end of said spring being in engagement with said retaining plate; and a wire fork having one end supported in said sleeve and its other end in engagement with said grade-wire to pivot in a vertical plane about said support mounting in response to variations in tool height relative to said grade-wire.

7. A support for a grade-wire adapted to be extended along the path of movement of a road building machine so that the grade-wire may be engaged by a wire fork mounted to said road building machine, said support comprising: a stake; and a wire hanger having one end thereof adjustably connected to said stake, the other end of said wire hanger including a short slot and a vertically extending fork spreading plate having a diagonally positioned slot extending there through and communicating with said short slot, the vertical dimension of said fork spreading plate being defined by two smooth arcuate concavely

opposed surfaces intersecting at edges lying in a horizontal plane at substantially the level of said short slot.

8. A support for a grade-wire adapted to be extended along the path of movement of a road building machine, said support being adapted to permit smooth uninterrupted engagement of a wire fork mounted to said road building machine with said grade wire, said support comprising: a ground support stake and a wire hanger having one end thereof adjustably connected to said stake, the other end of said wire hanger including a vertically extending fork spreading plate having a diagonally positioned slot extending there through and into said wire hanger, portions of said slot being conditioned to support and retain a grade-wire, said fork spreading plate having two concavely opposed surfaces intersecting in a horizontal plane containing said slot portions, said opposed surfaces being operative to gently force apart the prongs of a wire fork moving along a grade-wire into engagement with said surfaces to permit said wire fork to remain in its extended position during movement of a road building machine on which said fork is mounted.

9. A support for a grade-wire comprising: a plurality of stakes and a wire hanger having one end thereof adjustably connected to each of said stakes, the other end of said wire hanger including a vertically extending fork spreading plate having a diagonally positioned slot extending therethrough and into said wire hanger, said slot being dimensioned for grade-wire reception and portions thereof on said wire hanger being conditioned to retain and support a grade-wire, the vertical dimension of said fork spreading plate lying between two smooth concavely opposed and intersecting surfaces and gradually decreasing from its center position to its points of intersection in a common plane containing said slot portions.

10. In combination with an earth working vehicle having control means for varying the position of an earth working tool thereon transverse to a surface being worked in relation to disposition of a grade wire, a surface detecting and controlling assembly comprising:

a fork assembly extending from said vehicle and pivotally mounted thereon for oscillatory movement in a plane transverse to a surface being worked thereby, means operating said control means in response to said oscillatory movement,
said fork assembly including a pair of prongs spreadable in said transverse plane,
a plurality of wire hangers,
a grade wire retaining slot in each of said wire hangers, said prongs being adapted to engage said grade wire and move therewith along with said vehicle,
mounting means for supporting said wire hangers with said retaining slot at a selected distance from the surface being worked,
each of said wire hangers including a fork spreading member including a pair of opposed surfaces diverging vertically in the direction of vehicle travel from points within boundaries defined by the upper and lower surfaces of a retained grade wire.

11. The combination defined in claim 10 including:
a second pivotal mounting on said vehicle supporting said fork assembly for oscillatory movement in a plane parallel to said surface being worked, and
yieldable means urging said fork assembly into a centered position about said second pivotal mounting generally perpendicular to the direction of vehicle movement.

12. In combination with an earth working vehicle having control means for varying the elevation of an earth working tool thereon, a surface detecting and controlling assembly comprising:

a fork assembly extending from said vehicle and pivotally mounted thereon for oscillatory movements in a plane perpendicular to the direction of vehicle travel, means for operating said control means in response to said oscillatory movements,

a pair of prongs on the free end of said fork assembly spreadable in said perpendicular plane,
a plurality of wire hangers,
a grade-wire retaining slot in each of said wire hangers,
said prongs being adapted to engage said grade-wire 5 and move therealong with said vehicle,
mounting means for supporting said wire hangers with said retaining slot at a selected elevation above a surface being worked, and
a fork spreader on each of said wire hangers having a 10 pair of surfaces diverging in the direction of vehicle travel,
said surfaces intersecting in a plane containing said retaining slot.
13. The combination defined in claim 12 including: a second pivotal mounting on said vehicle supporting said fork assembly for oscillatory movement in a plane parallel to the direction of vehicle travel, and yieldable means urging said fork assembly into a 15 centered position about said second pivotal mounting generally perpendicular to the direction of vehicle movement,
said yieldable means being strong enough to resist movement of said fork assembly in said parallel plane 20 upon engagement thereof with a fork spreader to cause said prongs to spread and pass thereover and resume engagement with said grade-wire.
14. The combination defined in claim 12 including: 25 yieldable means urging said fork assembly upward in said perpendicular plane to counterbalance the effect of gravity thereon so that said grade-wire need not support said fork assembly as it moves therealong.

15. A wire fork assembly for controlling the tool elevation of an earth working vehicle in accordance with a ground supported grade-wire extending along the path of movement of said vehicle, said wire fork assembly comprising:
a control member rotatably mounted on said road building machine for limited angular displacement about an axis parallel to the path of vehicle movement,
said control member being operative to actuate control means for adjusting said tool elevation in response to the angular position of said control member about said parallel axis;
a fork assembly mounted on said control member to rotate therewith,
said fork assembly extending laterally from said vehicle and terminating in a pair of prongs operative to engage a grade-wire;
a swivel connection in said fork assembly to permit said prongs to move about a vertical axis; and
a closely wound extension coil spring secured across said swivel connection for normally centering said fork assembly about said vertical axis and in lateral extension.
